(57) **CLAIM**

The ornamental design for a baby sleeping bag as shown and described.

DESCRIPTION

FIG. 1 is a perspective view of a baby sleeping bag, illustrated as laid flat, showing my new design; FIG. 2 is another perspective view thereof, illustrated as laid flat;

FIG. 3 is a front view thereof, illustrated as laid flat; FIG. 4 is a rear view thereof, illustrated as laid flat; FIG. 5 is a front view thereof, illustrated as laid flat and in a partially open configuration;

FIG. 6 is a front view thereof, illustrated as laid flat and in another partially open configuration;

FIG. 7 is a front view thereof, illustrated as laid flat and in a fully open configuration;

FIG. 8 is a perspective view of the baby sleeping bag, illustrated as worn by a baby; and,

FIG. 9 is another perspective view thereof, illustrated as worn by a baby.

The broken lines in FIGS. 8-9 showing a baby are included to show the invention in use, and form no part of the claimed design. The remaining broken lines in FIGS. 1-9 depict portions of the baby sleeping bag that form no part of the claimed design.

1 Claim, 9 Drawing Sheets
